UNITED STATES PATENT OFFICE.

FREDERICK WEHINGER, OF WATERBURY, CONNECTICUT, ASSIGNOR TO WATERBURY CLOCK CO., OF WATERBURY, CONNECTICUT, A CORPORATION.

CHIME CLOCK.

1,406,511.

Specification of Letters Patent. Patented Feb. 14, 1922.

Application filed November 10, 1921. Serial No. 514,342.

To all whom it may concern:

Be it known that I, FREDERICK WEHINGER, a citizen of the United States, residing at Waterbury, in the county of New Haven and

- 5 State of Connecticut, have invented a new and useful Improvement in Chime Clocks; and I do hereby declare the following, when taken in connection with the accompanying drawings and the characters of reference 10 marked thereon, to be a full, clear, and exact description of the same, and which said drawings constitute part of this application, and represent, in—

Fig. 1 a view in front elevation of a chime-clock movement embodying my invention, members of the time-train being eliminated for clarity, as well as the strike-train. As shown, the clock is about to chime the half-hour, whereas, according to the position of 20 the time-train, it should be prepared to chime the quarter-hour.

Fig. 2 an edge view thereof.

Fig. 3 a view corresponding to Fig. 1, showing the time-train in its three-quarter hour position, and the chime-train warned and in position to chime the full hour, which it is prevented from doing by the depression of the chime-correcting unit into its guard position.

30 Fig. 4 a detached perspective view of the outer lever of the chime-correcting unit.

Fig. 5 a corresponding view of the inner lever thereof.

It is well known that chime clocks are 35 constantly giving trouble, due to the failure, for one cause or another, of their chime- and time-trains to synchronize. Among the causes which destroy such coordination, the setting forward and the setting backward 40 of the hands or pointers are, perhaps, the commonest, though such clocks often have the synchronization of their chime and time mechanisms dislocated by the failure to wind them seasonably, thus permitting their time 45 mechanisms to continue to operate after their chime mechanisms, which require more power, have stopped. Thus, chime clocks often become a source of great inconvenience and confusion, due to the failure of their 50 mechanisms to synchronize, although their mechanisms, as mechanisms, may each function perfectly. Much ingenuity and effort have been expended in attempts to overcome the difficulties above recited. The object of 55 my present invention is to avoid the above

objections to chime clocks and to provide simple and reliable means for the hourly automatic synchronization of the time and chime mechanisms of chime clocks.

With these ends in view, my invention 60 consists in a chime clock having chime- and time-trains, and a frictionally-mounted, chime-correcting unit moved into its guard position by the chime-train and into its clearance position by the time-train. 65

My invention further consists in a chime clock having certain details of construction and combinations of parts as will be herein-after described and particularly pointed out 70 in the claims.

In carrying out my invention, as herein shown, I employ a frictionally-mounted, chime-correcting unit comprising an outer chime-correcting lever 10, an inner chime-correcting lever 11, and a short rockshaft 12 75 journaled in the front movement-plate 13, the lever 10 being fixed upon the forward end of the said shaft, while the lever 11 is removably attached thereto by means of a set-screw 14 in a hub 15, to which the lever 11 is secured. A helical spring 16, encircling the inner end of the shaft, is compressed between the inner face of the plate 13 and the inner lever 11, and frictionally restrains the rocking of the shaft 12 and hence 80 the movement of the levers 10 and 11, except as the lever 10 is positively engaged, as will be described later on, to move the unit into its guard and clearance positions, in 85 which it is frictionally held by the said spring. 90

For hourly bringing the two levers 10 and 11 of the chime-correcting unit into its guard position, in which the unit discharges 95 its chime-correcting function, I employ a special chime-correcting pin 17 mounted in the count-wheel 18 of the chiming mechanism, to extend inwardly and outwardly from the plane of the said wheel, so as to provide for the utilization of both of its 100 ends, its inner end being utilized for co-action at about the point 19 thereon with the upper edge of the correcting-lever 10 for depressing the same against the friction developed by the spring 16 and thus rocking 105 the shaft 12 and correspondingly depressing the inner chime-correcting lever 11, so as to bring the stop-finger 20 at the end thereof into the path of a stop-pin 21 in the third wheel 22 of the chime-train, which may be 110

of any approved construction and arrangement. The chime-correcting unit is thus positively moved by the chime-train itself into its guard position.

- 5 As herein shown, the pin 17 is positioned in the count-wheel 18, so as to cause the time-train to move the chime-correcting unit into its guard position at the conclusion of the chiming of the third quarter of the 10 hour, when the stop-finger 20 of the lever 11 is moved into the path of the stop-pin 21 of the third wheel 22 of the chime-train, but it will be understood that the finger 20 and the pin 21, though hourly brought into 15 conjunction as described, never actually co-operate for stopping the chime-train unless the same and the time-train have fallen out of proper synchronism, the normal stopping of the chime-train being effected in the 20 usual manner by the movement of the stop-finger 23 of the locking-lever 24, into the path of a stop-pin 25 carried by the fourth wheel 26 of the chime-train. The said stop-finger 23 extends rearwardly through an 25 opening 27 in the movement-plate 13.

Inasmuch as the automatic hourly operation of the chime-correcting unit brings it into position for potentially stopping the chime-train, in case the same has fallen out 30 of synchronism with the time-train, provision must be made for hourly cutting it out of action by moving it into its clearance position, so that it will not prevent the normal operation of the chime-train, in case 35 the same is synchronous with the time-train.

For the purpose of hourly moving the said unit into its clearance position the inner end of its chime-correcting lever 10 is arranged to extend over and in close proximity to the upper edge of the horizontal operating-arm 28 of the chime-warning lever 29, which rocks upon a stud 30 in the movement-plate 13, and is held in its normal position by a helical spring 31, the upper end 40 of this lever being bent inwardly to form a stop-finger 32 extending through an opening 33 in the plate 13 into position to co-act with the stop-pin 25 carried by the fourth wheel 26 of the chime-train. The said operating-arm 28 extends over and is engaged 45 with and operated by a turn-back lever 34, pivoted on a stud 35, having a counter-weighted end 36 and formed with an operating-tooth 37 co-acting with each of four pins 50 38, 39, 40 and 41 projecting inwardly from a pin-disk 42 mounted upon the center arbor 43 at a point adjacent to the front face of the front plate 13 and constituting in effect 55 a member of the time-train, which thus becomes the prime-mover in restoring the unit 60 into its clearance position.

As shown, the pin-disk 42 is located directly back of the cannon-pinion 44, which is meshed into by the minute-wheel 45, 65 which carries a minute-pinion 46 meshing

into the hour-wheel 47, this "dial work" being of the ordinary form and construction.

The pins 38, 39, 40 and 41 aforesaid are arranged quartering with respect to each other and successively operate at quarter-hour intervals upon the turn-back lever 34 for lifting the warning-lever 29 against the tension of its spring 31. Of these pins, the pin 38 is a quarter-hour pin, the pin 39 the half-hour pin, the pin 40 the three-quarter-hour pin, and the pin 41 the hour-pin. Of these four pins, the hour-pin 41 is placed near the edge of the pin-disk 42 than the pins 38, 39 and 40, causing it to give a greater throw than the same to the turn-back lever 34, so that the said lever, acting through the medium of the operating-arm 28 of the chime-warning-lever 29 will, when the pin 41 is in play, raise the chime-correcting lever 10 and hence correspondingly lift the chime-correcting lever 11, so as to remove the stop-finger 20 thereof from the path of the stop-pin 21 in the third wheel 22 of the chime-train. In other words, the pin 41 acts to move the chime-correcting unit into its re-tired or clearance position. The action just above described automatically takes place only at the beginning of the time that the chime mechanism is due to chime the full hour, and regardless of whether or not the chime-train and the time-train have, during the preceeding hour, fallen out of synchronism.

The chime-correcting pin 17 in the count-wheel 18 is positioned to depress the chime-correcting-levers 10 and 11 only at the termination of the chiming on the third quarter of the hour, at which time only will the stop-finger 20 be brought into the path of the stop-pin 21 on the third wheel 22. The stop-finger 20 will remain in the path of the pin 21 thereafter only for the period of the ensuing quarter hour, when the chiming mechanism is due to chime on the full hour, at which time the hour-pin 41 in the disk 105 42 will operate the turn-back lever 34 to lift the chime-correcting unit so as to remove the stop-finger 20 from the path of the pin 21, and so release the chime-train, so far as the said unit is concerned.

At quarter-hour intervals, the pins 38, 39 and 40 will operate the turn-back lever 34 in operating the chime-warning lever 29, but owing to their positions nearer the arbor 43, they will not impart a sufficient throw to the turn-back lever 34 to effect a sufficient operation of the lever 10 to lift the stop-finger 20 out of the path of the stop-pin 21.

The outer end of the chime-correcting pin 17 in the count-wheel 18 is utilized for gradually lowering the rack (not shown) of the hour-strike mechanism, whereby the objectionable click, due to the abrupt descent of this rack, is prevented. By employing the outer end of the pin 17 for this purpose,

I am able to dispense with a separate pin therefor, as has been done heretofore.

Having now described the structure of my improved chime clock, I will proceed to set forth the mode of its operation, first describing its operation when the time and chime mechanisms are coordinating, as designed, and second, describing the automatic re-coordination of these two mechanisms after 10 they have been assynchronized for one reason or another.

In the normal operation of my improved clock, the clock chimes every quarter hour, and, after chiming, strikes on the hour. 15 Meanwhile, the chime-correcting unit constituting the salient feature of my present invention remains inactive, with the exception that immediately after the chiming on the third quarter of the hour, the pin 17 in 20 the count-wheel 18 engages, at the point 19, with the upper edge of the outer chime-correcting lever 10 and depresses the unit as a unit, against the friction developed by its spring 16, with the effect of approximately 25 engaging the end of the lever 10 with the operating-arm 28 of the chime-warning lever 29, and with the further effect of moving the stop-finger 20 of the lever 11 into the path of the stop-pin 21 on the third 30 wheel 22 but not into engagement therewith, since just prior to this action, the chime-train has been arrested by the engagement of the stop-pin 25 with the inwardly-turned stop-finger 23 of the locking-lever 24 in the 35 ordinary manner. The chime-correcting unit is held in this,—its guard,—position by the friction developed by the spring 16 substantially during the ensuing quarter-hour, near the end of which the hour-pin 41 40 in the disk 42 lifts the turn-back lever 34 sufficiently to act through the medium of the operating-arm 28 of the chime-warning lever 29 to lift the lever 10 and hence the chime-correcting unit against the friction 45 developed by the spring 16, whereby the stop-finger 20 is removed from the path of the pin 17. This may be described as the clearance action of the unit. At the same time, the lifting of the chime-warning lever 50 29 operates through its arm 48 to lift the locking-lever 24, whereby the stop-finger 23 thereof is removed from the path of the stop-pin 25 in the fourth wheel 26, which now turns until the said pin 25 engages with 55 the inwardly-turned end 32 of the chime-warning lever 29. Now, when the pin 41 passes the tooth 37 of the turn-back lever 34, the same drops into its retired position, permitting the lever 29 60 so as to remove its stop-finger 32 from the path of the stop-pin 25, and thus release the chime-train for chiming the hour. The duration of the chime is controlled by the co-action in the usual manner of the notches 65 in the count-wheel 18, with a pin 49 in the locking-lever 24. It will thus be seen that in the normal operation of my improved clock, the chime-correcting unit is automatically brought into its guard position on the third quarter of the hour, and returned to its 70 clearance position concurrently with the warning of the chiming-train on the full hour.

Now let it be supposed that, for some reason or other, and for the purpose of this 75 illustration it does not matter what, the chime mechanism of the clock has fallen out of synchronism with the time mechanism of the clock. As shown in Figures 1 and 2, the chime mechanism is a quarter of an hour 80 ahead of the time mechanism. In other words, the chime mechanism is prepared to chime as for the half hour, while it should be prepared to chime as for the quarter hour, since the time mechanism is just completing its quarter-hour phase. 85

As shown in Figure 1, warning has taken place and the tooth 37 of the turn-back lever 34 is about to drop off the quarter-hour pin 38 in the pin-disk 42. Now, when the pin 38 90 passes the tooth 37, the chime-train will be released in the ordinary manner, and the chime will be sounded as for the half hour, rather than as for the quarter-hour, which it should. At substantially the 95 end of the succeeding quarter hour, the half-hour pin 39 will operate the turn-back lever 34 in releasing the chime-train, whereupon the clock will chime as for the three-quarter hour, when it should chime as for the half 100 hour. At the conclusion of this chiming as for the third quarter of the hour, the pin 17 in the count-wheel 18 will engage at about the point 19 on the lever 10 and move the chime-correcting unit into its depressed or 105 guard position, as shown in Figure 3, whereby the stop-finger 20 of the lever 11 will be brought into the path of the stop-pin 21 on the third wheel 22 of the chime-train. At substantially the end of the next succeeding 110 quarter-hour, the three-quarter-hour pin 40 co-acts with the tooth 37 of the turn-back lever 34 with the effect of lifting the chime-warning lever 29, the arm 48 of which lifts the locking-lever 24 so as to move its stop-finger 23 from engagement with the stop-pin 25 of the fourth wheel 26, which now turns until its stop-pin 25 is brought into engagement with the stop-finger 32 of the chime-warning lever 29. The parts are then in the 115 positions shown in Figure 3. Now when the three-quarter hour pin 40 passes the tooth 37 and permits the turn-back lever 34 to drop and release the chime-warning lever 29, the finger 32 thereof will be removed from the 120 path of the pin 25 in the fourth wheel 26. The chime-train will now momentarily start, but will be almost immediately stopped by the engagement of the pin 21 in the third wheel 22 with the stop-finger 20 of the 125 130

chime-correcting lever 11, whereby the chime will be restrained from chiming on the third-quarter of the hour. During the ensuing fifteen minutes, the hour-pin 41 will have been brought into position to co-act with the tooth 37 of the turn-back lever 34, and as this pin is set as described so as to impart a greater throw to the lever 34, it will act through the operating-arm 28 to restore the chime-correcting unit to its clearance position, in which its stop-finger 20 will be moved out of the path of the pin 21 in the third wheel 22, but this will not cause the release of the chime-train, which will be restrained in the usual manner by the co-action of the stop-finger 32 of the warning-lever 29 with the stop-pin 25 in the fourth wheel 26, this wheel having made nearly one more revolution than under normal conditions to bring the pin 25 into engagement with the stop-finger 32. Now, when the hour-pin 41 passes the tooth 37 of the turn-back lever 34, the chime will be sounded as on the hour. The chime and time mechanisms have thus been restored to synchronization by nullifying one action of the chiming mechanism, with the effect of allowing the time mechanism, so to speak, to catch up with the chime mechanism. It will thus be seen that my improved chime-correcting unit, as constructed and arranged, prevents the chiming of the clock as on the full hour at any other time than on the full hour, irrespective of whether the want of synchronization between the time and chime mechanisms is represented by a quarter of an hour, a half hour, or three-quarters of an hour, inasmuch as the said unit is potentially brought into play once an hour on the third quarter thereof for correcting any want of synchronization, should any exist.

As herein shown and described, the pin 17 is positioned in the count-wheel 18 so as to cause the chime-train to itself move the chime-correcting unit into its guard position directly after chiming the three-quarter hour. In consonance with the described location of the pin 17, the full-hour pin 41 is placed nearer the edge of the disk 42 than the other pins therein, so that the unit will be moved into its clearance position under the control of the time-train, concurrently with the warning of the chime-train on the full hour. But this arrangement, though preferred, is not necessary, as the pin 17 might be placed so as to cause the chime-train to move the unit into its guard position, after chiming the quarter-hour, the half-hour, or the full-hour, in which case, the pin offset in the disk would have to be correspondingly changed. However, the logical time to synchronize the time and chime mechanisms is on the hour. It thus

appears that the principle underlying my invention is the utilization of the chime-train itself for moving my frictionally-mounted, chime-correcting unit into its guard position, leaving the moving of the unit into its clearance position entirely under the control of the time-train, which acts in this manner only when it has caught up with the chime-train and is again synchronous therewith, the said unit being held in its guard or clearance positions by friction. With my improved chime-correcting unit, the chime may conceivably be sounded three successive times out of consonance with the time indicated by the hands of the clock, but no more, depending upon the time within the hour when the chime-train and the time-train fall out of synchronism. On the other hand, the chime-train may move the unit into its guard position, so as to stop the chiming of the clock altogether for three successive times, but no more.

I claim:

1. A chime clock having time- and chime-trains, and a frictionally-mounted, chime-correcting unit, moved into its guard position for preventing the chime from sounding by the chime-train and into its clearance position under the control of the time-train and held by friction in its respective positions.

2. A chime clock having time- and chime-trains, and a frictionally-mounted, chime-correcting unit comprising two levers, one of which acts as a stop for the chime-train and the other of which is operated upon by the chime-train for moving the unit into its guard position, and means under the control of the time-train for moving the unit into its clearance position, the said unit being held in its respective positions by friction.

3. A chime clock having a time-train and a chime-train, and a frictionally-mounted, chime-correcting unit comprising two levers mounted upon a rock-shaft in one of the movement-plates of the clock, one of the said levers acting as a stop-lever for the chime-train and the other lever being acted upon by the chime-train for moving the unit into its guard position and also co-acting with the warning-lever of the time-train, which controls the movement of the unit into its clearance position, the said unit being held in its respective positions by friction.

In testimony whereof, I have signed this specification in the presence of two subscribing witnesses.

FREDERICK WEHINGER.
